[57] **CLAIM**

The ornamental design for an exterior surface configuration of a motor vehicle rear light assembly, as shown and described.

DESCRIPTION

FIG. 1 is a rear view of an exterior surface configuration of a motor vehicle rear light assembly according to my/our novel design;

FIG. 2 is a perspective view from the rear right side of the exterior surface configuration of a motor vehicle rear light assembly; and,

FIG. 3 is a side view of the exterior surface configuration of a motor vehicle rear light assembly.

The broken lines which appear in FIGS. 1, 2 and 3 are showing for illustrative purposes only and form no part of the claimed design.

Features shown in dash lines depict the environment and do not form part of the claimed design.

The drawings illustrate the exterior surface configuration of a right side of a motor vehicle rear light assembly asymmetrically arranged, a left side motor vehicle rear light assembly being a further embodiment of the novel design which is not illustrated since it is symmetrical to the one illustrated.
